UNITED STATES PATENT OFFICE

ARTHUR J. RAY, OF CHICAGO, ILLINOIS, ASSIGNOR TO ASSOCIATED TELEPHONE AND TELEGRAPH COMPANY, OF KANSAS CITY, MISSOURI, A CORPORATION OF DELAWARE

TELEPHONE SYSTEM

Application filed September 29, 1927, Serial No. 222,741, and in Great Britain October 14, 1926.

The present invention relates to telephone systems and is more particularly concerned with what is known as routine testing apparatus, that is to say apparatus arranged to reproduce automatically the actual conditions of use for each unit in turn of a large group of similar pieces of apparatus. The invention also is intended to be applied more particularly to the testing of apparatus which can only be tested while it is not actually in use and must not be busied to its normal means of access in order that a test may take place. It is generally recognized nowadays that routine testing is desirable, if not essential, particularly for complicated apparatus, in order that it may be possible to anticipate faults rather than correct them after they occur, and for the test to be effective it is essential that every piece of apparatus shall be tested. This clearly presents a difficulty in the above-mentioned circumstances, and it is the main object of the invention to deal with cases of this sort in a simple manner.

According to one feature of the invention in an automatic testing arrangement having a hunting switch for associating with the testing equipment the various pieces of apparatus to be tested, idle pieces of apparatus are tested in turn until all have been dealt with and a piece of apparatus is adapted to be prevented from seizure by the hunting switch in consequence of a special potential associated therewith due to the completion of the test.

A further feature of the invention is the provision of an automatic testing arrangement for the routine testing of telephone apparatus when such apparatus is not in use in which means associated with the testing equipment enable particular pieces of apparatus to be associated with said equipment when in use so that certain tests may be carried out in conjunction with the user of the apparatus.

These features and others not specifically mentioned at this point will be better understood from the following description of one method of carrying the invention into effect which should be taken in conjunction with the accompanying drawings. Clearly any routine arrangement will need to be specially designed in view of the apparatus it is desired

to test and the arrangement shown has been designed for the testing of key-sending operators' positions of the type described in British Patent No. 229,765. It will be recalled that in the arrangement disclosed in 55 this specification, calls passed to a B operator over an order wire are set up on a single set of digit keys the operation of which serve to control an impulse sender to send out the necessary trains of impulses for operating 60 automatic switches to connect with the wanted line. As a general rule the B operator will have 40 trunks incoming to her position, though in particular cases this number may be increased to 50. Moreover, in view of the 65 fact that the complete operation of an impulse sender takes several times as long as the setting of the digit keys, it is arranged that as many as four impulse senders can be associated with her position at a time in order 70 that she may work continually at full speed, the impulse senders being accessible in common to a considerable number of operators. The testing of the complete apparatus falls naturally into two parts, one comprising the 75 testing of the actual impulse senders which may be done as described in British Patent No. 267,606 and the other the testing of the junction relay sets and apparatus for associating impulse senders with the operator's key-set. A little consideration will show that for a complete test to be carried out it is necessary to employ the apparatus at the operator's position used for associating an idle impulse sender with that position, hence it follows 80 that the test cannot be carried out while the position is in service.

Referring now to the drawings comprising Figs. 1-8; Figs. 1 and 2 show the various controlling keys and a number of the associated 90 relays; Figs. 3 and 4 show a further group of the relays controlling the routiner; Figs. 5 and 6 show the test switch TS, the routine indicating switch RIS and the number-set-up switch NS, together with the fault indicating 95 lamps for indicating the progress of a particular test; while Figs. 7 and 8 show the distribution equipment by means of which connection is made with each position in turn, and also with each junction in turn at a par- 100

ticular position. In order to facilitate the understanding of the circuit, the description will be divided into two parts, firstly consideration of the arrangements by which connection is made in turn to the various positions and each junction at the position is tested, and secondly consideration of the actual tests which are carried out on the junction and the circuit arrangements by means of which they are applied.

Considering first, therefore, the distribution equipment in the arrangement shown, it is assumed that the test set is to serve for 60 operators' positions and that each position has 50 incoming junctions and means for associating four impulse senders with the position at a time. The position distribution equipment comprises a primary distributor PD from which access is had to three secondary distributors SD¹—SD³ of which only SD¹ and SD³ are shown since the circuits of SD² are similar. Preferably the contacts of the primary distributor PD are multiplied round the bank as shown in Fig. 7, so as to avoid unnecessary operation of the switch. Since it is not found possible to provide the secondary distributors with sufficient wipers for all the functions which they are required to perform, each one has associated with it an auxiliary secondary distributor of which only the auxiliary secondary distributor ASD¹ associated with the switch SD¹ is shown in Fig. 8. Each secondary distributor is wired to have access to 20 operators' positions and when all the 20 have been tested or found busy, the primary distributor is advanced so as to connect up the succeeding secondary distributor. Associated with each position are a pair of junction distributors such as JD¹ and JD², shown in Fig. 8, which are given access to a maximum of 24 and 22 junctions respectively. Where the full 50 junctions are equipped, access is obtained to the last four over the first four contacts of the distributor JD¹, a suitable switching operation being performed to connect these junctions up in place of junctions 1—4 as will be described subsequently. The junction distributors are provided with a normal position in which the contacts are left dead and by this means the wipers of the junction distributors associated with all the positions may be multiplied together to the routine test set and the position distributors ensure that the junction distributors of only one position shall be operated at a time. It should be mentioned with reference to Fig. 7 that the banks of wipers 618—620 of the secondary distributor SD³ are wired to the various junction distributors in the same manner as is indicated by the wiring of the first contacts in the banks of SD¹. The bank of wiper 617 is wired to the contacts of the associated position battery feed relays while that of wiper 621 is wired to the bank of the associated auxiliary secondary distributor

ASD³. The switch SD² is wired similarly. As regards the auxiliary secondary distributor ASD¹, Fig. 8, over wipers 639 and 640 of this switch access is had to the order wire leads of the various positions, while over wipers 641—644 connections are made to the four leads extending from the operator's key-set so that a test number may be set up from the routiner. Over wiper 645 circuits are completed for changing over from junctions 1—4 to junctions 47—50 where this is necessary. The other auxiliary secondary distributors are wired in a similar manner. The bank of wiper 625 of the junction distributor JD¹ is wired to the lamp leads of the various junctions, that of wiper 626 to the respective assignment leads and those of wipers 627 and 628 to the negative and positive trunk conductors respectively.

The operations involved in making a test will now be considered in detail. In order to set the routiner in operation, the attendant operates the start key SK whereupon a circuit is completed for relay 115. Relay 115 upon operating, at armature 116 prepares a circuit for the test relay 131, at armature 117 completes a circuit for the relay 119 and at armature 118 prepares the pulsing circuit to the first secondary distributor. Further, at armature 122 relay 115 completes a circuit for relay 127 which extends as follows: battery, winding of magnet 507 of the switch TS, lead 439, armature 313 and its back contact, lead 726, lead 441, interrupter contacts 508, wiper 506 and its normal contact, lead 93, winding of relay 127, armature 122 and its front contact. Relay 119 now operates and at armature 120 opens the circuit of relay 280 which is normally energized in the following circuit: battery, relay 280, lead 698, lead 407, normal contact and wiper 622 of the switch SD³, normal contact and wiper of the switch SD² represented by the link 624, normal contact and wiper 616 of the switch SD¹, lead 18, lead 664, armature 120 and its back contact to earth and at the front contact of armature 120 extends earth over lead 686, lead 26, wiper 603 of the primary distributor PD, lead 23, winding of relay 215 to battery so that relay 215 is operated and prepares circuits for the junction distributors and auxiliary secondary distributor and also for the relay 185. Furthermore at armature 121 relay 119 prepares a circuit for stepping the junction distributors. At armature 129 relay 127 prepares circuits for relays 152 and 180 and at armature 130 closes the pulsing circuit of the secondary distributor. Relay 119 moreover at armature 123 opens the homing circuit of the primary distributor and provides a locking earth, at armature 124 prepares a circuit for stepping the primary distributor after each secondary distributor has rotated over all positions connected to it, at armature 126 opens an alarm circuit over lead

57 and at armature 125 connects earth to motor start lead 94 and opens the normally closed circuit for relay 278 which extends as follows: battery, winding of relay 278, lead 714, lead 493, lead 845, link 649 representing 5 wipers and normal contacts of all the junction distributors not shown, normal contact and wiper 637, normal contact and wiper 630, lead 1, lead 665, back contact and armature 125 to earth. Relay 278 now de-energizes thereby altering certain supervisory circuits as will be described subsequently. The pulsing circuit completed on the operation of relay 127 extends from earth, winding of relay 264, armature 267 and its back contact, lead 47, armature 148 and its back contact, lead 61, back contact and armature 286, lead 62, armature 136 and its back contact, armature 118 and its front contact, front contact 10 and armature 130, armature 153 and its back contact, armature 167 and its back contact, lead 666, lead 27, wiper 605 of the primary distributor and the first contact in its bank, winding of magnet 610 of the secondary distributor SD¹, lead 29, winding of relay 233 to battery. In this circuit the battery feed relay 233 is operated and at armature 234 completes a supervisory circuit which will be more fully described later. Moreover magnet 610 is 15 operated and attracts its armature preparatory to advancing the wipers of the switch SD¹ and relay 264 is also operated and at armature 265 completes a circuit for relay 268. This relay at armature 269 completes a circuit for the slow-to-pull-up relay 266 which upon operating in due course, at armature 267 opens the circuit originally traced, whereupon relay 264 and magnet 610 fall back and the latter advances the switch SD¹ 20 one step. Relay 264 upon releasing, opens the circuit of relay 268 and this in turn brings down relay 266 whereupon unless the operator's position then connected with is in condition to be tested, magnet 610 is again energized and the cycle recommences. The relay 25 533 in Fig. 6 is used for feeding battery to the operator's headset and when the operator is absent from the position and has therefore withdrawn her headset plug, relay 533 is de-energized and extends earth over armature 534 and lead 408 to the first contact in the bank of the secondary distributor SD¹ over 30 which access is obtained to this position. It will be understood that the battery feed relays of the other operators' positions are connected up similarly to other contacts in the banks of the switches SD¹—SD². The secondary distributor continues to advance step-by-step owing to the pulses received from 35 relays 264, 266 and 268 until wiper 611 encounters a contact to which earth is connected owing to the operator being absent from the corresponding position. Thereupon the following circuit is completed: earth connected 40 to this contact over the back contact and

armature of the battery feed relay, wiper 611, first contact in the bank of wiper 601 and said wiper, lead 24, lead 691, lead 59, armature 289 and its back contact, lead 60, back contact and armature 160, back contact and armature 145, armature 116 and its front contact, winding of relay 131, resistance 276 to battery. Relay 131 is operated in this circuit and at armature 133 prepares a circuit for the magnet 631 of the junction distributor JD¹, at armature 134 completes a circuit for relay 152, at armature 135 closes another point in the circuit of relay 180 and at armature 136 disconnects the pulsing earth from the magnet of the secondary distributor SD¹ 45 and extends it to the magnet of the auxiliary secondary distributor ASD¹ over lead 676, front contact and armature 218, armature 191 and its back contact, lead 2, magnet 647, lead 840, lead 29 to battery through relay 233. Consequently the auxiliary secondary distributor now commences to step and this continues until relay 185 is energized when the auxiliary secondary distributor reaches the 50 same position as its associated secondary distributor. The circuit for relay 185 may be traced from earth, wiper 604 and its first contact, wiper 615, multiplying to wiper 646, lead 3, armature 219, and its front contact, winding of relay 185 to battery, and the operation 55 of the relay opens the stepping circuit at armature 191. When relay 152 operates, at armature 153 it opens another point in the pulsing circuit to the secondary distributor, at armature 155 completes a locking circuit 60 for itself which extends as follows: battery, winding of relay 152, armature 155 and its front contact, normally closed right-hand springs of the re-start key RS, armature 169 and its back contact, front contact and armature 123 to earth, at armature 156 opens a point in the circuits of the relays 137, 143 and 162, and at armature 157 prepares a circuit for homing the junction distributors. The 65 operation of relay 185 also at armatures 186—189 and 192 and 193 prepares the connection of the digit and order wire leads over leads 79—82 and 9 and 10 to the wipers of the auxiliary secondary distributor, and at armature 190 completes a circuit for relay 180 extending as follows: battery, winding of relay 180, front contact and armature 190, lead 671, front contact and armature 135, armature 129 and its front contact, front contact and armature 134, armature 169 and its back contact, front contact and armature 123 to earth. Relay 180 upon operating, at armature 181 completes a circuit for relay 229 and this locks up by way of armature 230, at 70 armature 182 completes the following circuit for relay 330; battery, winding of relay 330, lead 45, lead 683, armature 182 and its front contact, lead 682, lead 33, wiper 502 of the switch TS and the first contact in its bank, lead 453 and by way of interrupter 485 to 75

earth. Moreover at armature 183 earth is connected over leads 679 and 44, armature 331 and its back contact, lead 725, upper winding of supervisory relay 314 to battery, and at armature 184 the homing circuit of the test switch TS is opened and earth is connected to wipers 501 and 503. When the contacts of interrupter 485 next close, relay 330 is operated and at armature 331 opens the circuit of the relay 314, at armature 332 completes a direct circuit for magnet 507 and at armature 333 completes a locking circuit for itself extending as follows: earth, armature 332 and its front contact, lead 441, interrupter contacts 508, lead 429, armature 333 and its front contact, winding of relay 330 to battery. The connection of earth to wiper 501 completes a circuit for the first supervisory lamp 542 over lead 753, which lights to indicate that a free position has been found. When magnet 507 has operated fully and opened interrupter contacts 508, relay 330 de-energizes thereby opening the circuit of magnet 507 so that the switch TS is advanced one step. The earth connected to wiper 503 is now extended over lead 440, lead 35, back contact and armature 163, armature 121 and its front contact, front contact and armature 133, lead 667, armature 176 and its back contact, armature 216 and its front contact, lead 20, wiper 613 and the first contact in its bank, lead 806, magnet 631 of the junction distributor JD^1 , lead 402, winding of supervisory relay 295 to battery so that magnet 631 is operated. The succeeding pulse from interrupter 485 again operates relay 330 and this in turn effects the advance of the test switch. When the test switch takes its next step and advances to its third position, the circuit just traced is opened and accordingly the wipers of the junction distributor JD^1 are advanced one step. In case the position which has been connected with should only just have been vacated by the operator so that there is a call still in progress over the first junction, there will be earth on the lamp lead and this will accordingly be extended over the appropriate contact in the bank of wiper 625, lead 13, lead 74, lead 720, armature 340 and its back contact, lead 721, upper winding of relay 376 to battery. Moreover owing to the advance of the test switch, the initial circuit over lead 440 is opened and relay 334 is operated over wiper 503 and lead 443. Accordingly the following circuit is now completed: earth, relay 264, armature 267 and its back contact, lead 711, armature 379 and its front contact, lead 710, armature 335 and its front contact, lead 35 and thence over the circuit previously traced to the magnet of the junction distributor JD^1 . Consequently this switch is again operated and if one or more further busy junctions are encountered, relay 376 remains operated so that the movement continues until the switch JD^1

has been moved into engagement with a junction over which no call is in progress. Relay 376 will then de-energize and complete a circuit for advancing the test switch which now continues its operation and applies the various tests in turn to this junction as will be fully described subsequently. 70

When wiper 503 has made a complete revolution and again comes into engagement with the second contact in its bank, the circuit traced above again becomes operative for advancing the junction distributor, and in the ordinary course this will take only one step and the next junction will then be connected up for testing purposes. In case, however, 80 this junction should still be in use or should be out of service for any reason, there will be earth on the lamp lead and this will operate relay 376 to step the junction distributor on past this junction as above described. 85

As already pointed out, the switch JD^1 is arranged to deal with 24 junctions, and when its wipers are advanced into engagement with the last of these junctions, the following circuit is completed: earth, wiper 629 and the 90 24th contact in its bank, lead 12, winding of relay 172 to battery. Relay 172 upon operating, at armature 173 shunts armature 176 and its back contact and at armature 174 completes a circuit for relay 175. The latter upon operating, at armature 178 locks to earth at armature 123, at armature 176 prepares a circuit for the magnet 638 of the junction distributor JD^2 , and at armature 179 prepares an auxiliary circuit for the magnet of the junction distributor JD^2 . When the testing of this junction has been completed and the test switch again reaches position 2, earth is again connected to lead 440 and is extended to the magnets of both distributors JD^1 and JD^2 , 95 hence JD^1 is advanced to its 25th or normal contact and JD^2 takes one step and tests the first junction in its bank. When the switch JD^1 steps, the circuit of relay 172 is opened and it thereupon releases and prevents any further pulses being sent to magnet 631. If the first junction in the bank of JD^2 is idle and in service the usual tests are carried out thereon and the switch JD^2 is advanced one step to connect up a succeeding junction. 100 110

When all the junctions accessible from the bank of the switch JD^2 have been tested, the switch wipers will be advanced to position 23 whereupon a circuit is completed as follows: earth, wiper 636 and the 23rd contact in its bank, lead 11, lead 669, winding of relay 166 to battery. Relay 166 upon operating, at armature 167 opens a point in the circuit for stepping the secondary distributor, at armature 169 opens the circuit of relays 109, 152, 125 175 and 180, at armature 170 closes a point in the circuit of relay 285 and at armature 171 completes a circuit for stepping the junction distributor JD^2 a further step. When relay 180 de-energizes, earth is supplied at 130

armature 184 for homing the test switch and when this reaches normal position, relay 127 is operated. Relay 175 being slow to release holds up for a moment and when it de-energizes the wipers of the switch JD^2 are advanced a further step and the circuit of relay 166 is then opened and it slowly releases. With the wipers of JD^2 in the 24th position, the following circuit is completed: earth, 10 wiper 636 and the 24th contact in its bank, lead 805, first contact in the bank of wiper 612 and said wiper, first contact in the bank of wiper 602 and said wiper, lead 25, lead 673, armature 154 of relay 137, and its back 15 contact to the lower terminal of the winding of relay 131. Since the original earth connection to the other terminal of this winding is still intact, relay 131 is now short-circuited and accordingly de-energizes, thereupon at 20 armature 136 again connecting up the pulsing circuit from relay 264 for advancing the secondary distributor. Accordingly conditions are now similar to those obtaining when the test was started and the secondary distributor 25 SD^1 hunts to find an idle position. When such a position is found as indicated by the presence of earth on the associated contact in the bank of wiper 611, relay 131 again operates and at armature 136 completes the circuit 30 for advancing the auxiliary secondary distributor correspondingly. The appropriate junction distributor is then advanced one step and if necessary hunts to find an idle junction on which tests are made as before. 35 When all the positions accessible from the secondary distributor SD^1 have been tested or found busy, wiper 615 will be engaging the 21st contact in its bank and a circuit will then be completed as follows: earth, wiper 604 and the first contact in its bank, wiper 615 and the 21st contact in its bank, lead 403, winding of relay 297 to battery. Upon the operation of relay 297 a circuit is completed from earth, armature 124 and its front contact, lead 689, lead 69, armature 298 and its front contact, lead 168, winding of magnet 607 of the primary distributor, lead 29, winding of relay 233 to battery as before. Magnet 607 thereupon energizes but does not yet advance its associated wipers. Since relay 131 is still not operated a circuit is again completed for advancing the secondary distributor SD^1 and wiper 615 accordingly leaves its 45 21st contact. Consequently the circuit for relay 297 is now opened and its releases, thereby opening the circuit for the magnet 607 of the primary distributor which advances the wipers one step. The secondary distributor SD^2 is thus connected up and the 50 positions accessible over its bank are then tested in the manner previously described. When it arrives at position 21, a circuit is completed for advancing the primary distributor in the same way as above described, 55 and accordingly the secondary distributor 60 SD^3 is brought into action and the unstaffed positions accessible from its banks are duly tested. When all these positions have been dealt with, wiper 621 engages the 21st contact in its bank and a circuit is then prepared for relay 285 but this is not completed owing to the fact that it is held open at armature 231, relay 229 being operated at this time. Consequently the switch SD^3 continues to step in response to pulses from relay 264 until it engages its 23rd contact whereupon a circuit is completed from earth on wiper 604 as before, lead 401, winding of relay 292 to battery. Relay 292 upon operating at armature 293 opens the locking circuit of 65 relay 229 thus causing it to release and at armature 294 extends earth from lead 69 over lead 168 to the magnet 607 of the primary distributor and this is accordingly operated and steps its wipers so as to connect up the secondary distributor SD^1 again when the above circuit is opened due to the further stepping of the distributor SD^3 . 70 It has already been pointed out that the tests on an operator's position can only be made when the position is not in use and accordingly it will be clear that even if the routine testing is undertaken at times of light load as would normally be the case, a single operation of the routiner would be unlikely 75 to test all the operators' positions. It is therefore provided in the present instance that after all positions have been tested once for busy or idle condition and the idle ones 80 duly routined, the various positions are again tested, only on this occasion not only positions which are actually busy have to be passed over but also those which have been routined on the previous operation of the distributing switches. The necessary discrimination is effected due to the position which the second junction distributor takes up when a position has been completely routined. Reference to Figs. 7 and 8 will 85 show that in this case earth is applied over the 24th contact in the bank of wiper 636 of the junction distributor JD^2 to the contact associated with the position in the bank of wiper 612 and this will have the effect of 90 producing a short-circuit on relay 131, so that in the case of positions actually in use no earth is supplied to this relay and in the case of positions which are not in use but which have already been tested earth is supplied to 95 both terminals of the relay so that in either 100 event the relay is unable to operate. Accordingly it does not open the pulsing circuit to the secondary distributor and this switch steps over the position. It will be recalled 105 that when a free position is encountered, relay 131 operates and completes a circuit for relay 180 and this in turn operates relay 229 which locks up dependent upon relay 280 and 110 292. Hence if all the secondary distributors 115 should pass over the whole of their banks 120 125 130

without finding any position in a condition to be tested, relays 131, 180 and 229 will not be operated and in this case when wiper 621 of the secondary distributor SD^3 engages its 21st contact, earth is extended over lead 15, armature 231 and its back contact, lead 685, lead 65, upper winding of relay 285 to battery. Relay 285 is a two-step relay and at this time only operates its light armature 290 thereby short-circuiting its lower winding by earth on the left-hand contacts of the restart key RS. When the secondary distributor SD^3 receives a further pulse, the initial energizing earth is removed and relay 285 then operates fully over both its windings in series and is accordingly locked up to the re-start key RS. The operation of relay 285 at armature 291 completes a circuit for the routine finished lamp 284 and the lower winding of relay 314 in series and relay 314 operates with results to be described subsequently. Relay 285 moreover at armature 286 opens the normal pulsing circuit for the secondary distributors and auxiliary secondary distributors, at armature 288 opens an auxiliary energizing circuit for itself, at armature 289 opens a point in the circuit of relay 131 and at armature 287 connects earth to wiper 616 of secondary distributor SD^1 . This switch accordingly commences homing and when it has reached its normal position the homing earth is extended to the secondary distributor SD^2 . When this switch in turn has reached its normal position the homing earth is transferred to the switch SD^3 and when this switch has returned to normal a circuit is again completed over lead 407 for relay 280. Relay 280 upon operating, at armature 281 opens a further point in the locking circuit of relay 229 and at armature 282 opens a point in the magnet alarm circuit.

In case the attendant discovers by operating the key RIK that a number of positions have still not been tested, he may leave the routining apparatus in this condition for an interval and then by operating the re-start key RS, again set it to hunt for and routine positions which have not yet been dealt with. When the re-start key is pressed, the locking circuit for relay 285 is opened and it releases thereby completing the pulsing circuit for the distributor SD^1 . The operation now proceeds as before and continues until all three distributors again make a complete rotation without finding any position in condition to be tested. It will be noted that in these circumstances only the secondary distributors are restored to normal but not the junction distributors, since these switches indicate by their off-normal position that the associated position has already been tested. When the start key is restored, on the completion of the test or at any other time the circuit of relay 115 is opened and upon de-

energizing it opens the circuit of relay 119. Upon the de-energization of relay 119, a homing circuit for the secondary distributors is completed from earth over armature 120 and its back contact and leads 664 and 18 to wiper 616 of the distributor SD^1 whence it is extended in turn to distributors SD^2 and SD^3 . Over armature 123 and its back contact earth is applied over leads 688 and 28 to the bank of wiper 606 so that this is effective in bringing about the homing motion of the primary distributor. The earth over the back contact of armature 125 is extended over leads 665 and 1 to wiper 630 of the junction distributor JD^1 and serves to effect the homing motion of this switch. When the switch reaches its normal position, the homing earth is extended to the switch JD^2 and this in turn is operated to normal. All the other junction distributors accessible to the routiner are homed in a similar manner, one after the other, and accordingly all the apparatus is left in the position shown ready for a further test to be initiated, for instance the next day. The sole exception is the auxiliary secondary distributors for since they always follow their associated secondary distributors when they are required for use it is unnecessary to return them to a definite normal position. It may be mentioned also that with the arrangement shown, the operation of the key RS is necessary to bring down relay 285, but this could if desired be dependent on relay 115 so that it would release when the start key was restored.

Consideration may now be given to the actual tests which are made on each junction. The initial circuit for stepping the test switch TS has already been traced, this being completed owing to the operation of relay 330 when relay 180 is energized. It was pointed out, moreover, that with the test switch engaging its second set of bank contacts, a circuit is completed over lead 440 for advancing the first junction distributor of the seized position one step, the test switch meanwhile moving to engage its third set of contacts. In case the junction which is then connected with should have a call in progress or should be out of service, there will be earth on the lamp lead and accordingly the junction distributor will again be advanced under the joint control of relays 334 and 376. When relay 376 de-energizes, a circuit is completed for relay 330 extending as follows: battery, winding of relay 330, lead 45, lead 683, armature 182 and its front contact, lead 682, lead 33, wiper 502 and the third contact in its bank, lead 461, lead 736, back contact and armature 382, lead 735, interrupter 485 to earth, so that the switch TS is moved to fourth position. In this position a circuit is completed over the fourth contact in the bank of wiper 503 and lead 446 for relay 336. Upon the operation of relay 336, earth through the lower winding of relay 376 is connected over lead 724, front contact

and armature 340, lead 720, lead 74, lead 13 and over wiper 625 of the switch JD¹ to the lamp lead; if this lead is continuous, battery through the lamp will be operative to energize 5 relay 376. Moreover at armature 337 earth is connected over lead 709 through the winding of relay 389 and over lead 405 and wiper 628 to the positive trunk conductor. In case this 10 trunk should be in contact with any adjacent leads, a circuit will now be completed for relay 389 and it will thereupon operate. Furthermore at armatures 338 and 339 the windings of relay 385 are connected together and over leads 718 and 404 and wiper 627 to the 15 negative trunk conductor. The windings of relay 385 are connected in opposition so that if there is no potential on the negative conductor at this time, the relay will not operate but in case the negative line should be in contact 20 with some adjacent leads, relay 385 will be unbalanced and will therefore operate. The condition for a successful test is therefore that relay 376 should be operated but that relays 385 and 389 should not be operated. In these 25 circumstances no circuit is completed for the fault indicating lamps 538—540 which are wired to the fourth position of the test switch. It will be seen however that if relay 376 fails to come up, earth on lead 437 will be extended 30 over back contact and armature 378, lead 708, lead 438, lead 748, lamp 538, to battery. Similarly if relay 385 operates a circuit is completed over front contact and armature 386 and leads 706, 436 and 749 for lamp 539 and 35 if relay 389 operates lamp 540 is lighted over armature 390, lead 705, lead 435 and lead 750. A circuit is now completed from the interrupted generator 400 over lead 737, front contact and armature 383, back contact and armature 387, armature 391 and its back contact, lead 738, lead 462, fourth contact in the bank of wiper 502 and said wiper, lead 33, lead 682, front contact and armature 182, lead 683, lead 45, winding of relay 330 to battery. Relay 40 330 is accordingly operated and effects the advance of the test switch in the manner previously described. With the test switch in 5th position, a circuit is completed over lead 427, wiper 503 and lead 447 for relay 341. Upon 45 the operation of relay 341, battery through resistance 399 is connected at armature 342 over lead 709 through relay 389 to the positive trunk conductor and at armature 343 earth through the lower winding of relay 385 is 50 connected over lead 719 to the negative trunk conductor. Relay 385 only operates if there is battery on the negative line, while the resistance of relay 389 and resistance 399 in series is sufficiently high to prevent the operation 55 of two line relays in parallel if two positive lines should be in contact, but will allow one line relay to operate if there is no contact. Relay 389 is also now operated and the conditions set up by this test are equivalent to the 60 taking of the junction by an "A" operator before it has been assigned. Accordingly if the junction line relay has duly energized, the correct operation at this time is that the junction lamp should be caused to flicker. Hence since relay 336 released when the test switch 65 moved to fourth position the flicker pulses connected to the lamp lead are now transmitted over armature 340 and its back contact and lead 721 to the upper winding of relay 376. Each time relay 376 operates in response to the flicker the following circuit is completed: earth, armature 392 and its front contact, armature 388 and its back contact, armature 384 and its front contact, lead 740, lead 464, multiplied contacts 5, 6 and 7 in the bank of wiper 502, lead 33, lead 682, front contact and armature 182, lead 45, winding of relay 330 to battery. The operation of relay 330 as before effects the stepping of the test switch over the next three positions. In each 70 of these positions earth over wiper 501 is extended to the indicating lamp 543. 75

When the test switch reaches its 8th position, the circuit of relay 341 is opened and earth is connected over wiper 501 and the multiplied 8th, 9th, 10th and 11th contacts in its bank to the junction assigned indicating lamp 544. The stepping of the test switch over the 8th and 9th contacts is effected by earth from the interrupter 400 being extended over armature 329 and its back contact and lead 454 to the contacts engaged by wiper 502 whence a circuit is completed for relay 330 in the usual manner. While the test switch is in its ninth position, a circuit is completed from earth on wiper 503 to the ninth contact in its bank, lead 444, lead 745, lead 406 and wiper 626 to the assignment lead associated with the junction. Accordingly the junction is assigned and the 80 sender finder and junction finder at the operator's position are thereupon started up. Since both relays 336 and 341 are now de-energized both relays 385 and 389 are disconnected and the upper winding of relay 376 is connected as before to the lamp lead. When the sender 85 90 95 100 105 110 115 120 125 130

When the test switch reaches position 12, indicating lamp 545 is lighted and a circuit is completed over wiper 503 and lead 448 for relay 344 which accordingly operates. Thereupon at armatures 348—351 it connects wipers 525—528 of the number-set-up switch NS by way of leads 730—733 and 449—452, leads 763—767, leads 79—82, armatures 186—189 and leads 5—8 to wipers 641—644 of the auxiliary secondary distributor ASD¹ and at armature 345 completes the following circuit: earth, winding of relay 264, armature

267 and its back contact, armature 345 and its front contact, lead 713, lead 470, first contact in the bank of wiper 530 and said wiper, winding of magnet 531 to battery. Moreover at armature 346 it opens the homing circuit of the number-set-up switch and connects the commoning of contacts 2—16 to the pulsing lead from relay 264. Relays 264, 266 and 268 now interact in the manner previously described to send impulses and the switch NS is thus stepped round to effect the setting up of the digit storage relays in the impulse sender, this corresponding to the operation of the digit keys by the operator. It will be understood that the appropriate contacts in the banks of wipers 525—528 of the number-set-up switch are suitably jumpered to earth so as to effect the setting up of the test number which will secure that the test call is routed back to the routiner in a manner which will be more fully described subsequently. When the switch NS reaches its 16th position after having set up a full 7-digit number, a circuit is completed from earth on the 16th contact in the bank of wiper 529, lead 768, 12th contact in the bank of wiper 504, interrupter springs 508, lead 441, lead 726, back contact and armature 313, lead 700, lead 439, magnet 507 to battery. Accordingly the magnet is energized and since the above traced circuit includes the interrupter contacts 508, the test switch is advanced one step into the 13th position. In this position the circuit relay of 344 is broken and it de-energizes, thus disconnecting the wipers of the number-set-up switch and completing circuits to cause this to return to normal under the control of interrupter contacts 532. In the 13th position of the test switch indicating lamp 546 is lighted and a circuit is completed over wiper 503 and lead 456 for relay 352 which upon operating, at armature 356 locks to earth provided at armature 184 of the relay 180. Moreover at armature 354 it connects battery through resistance 399 and relay 389 over lead 709 to the negative trunk conductor and at armature 355 connects earth through the lower winding of relay 385 over lead 719 to the positive trunk conductor. This corresponds to the taking of the junction line by the "A" operator and causes the starting of the sender.

The code digits set up on the storage relay groups in the impulse sender in response to the operation of the number-set-up switch are now sent out, suitably translated so as to cause the routing of the call over a special test level in a selector whence connection is established back to the routiner over the leads 481, 482 and 483. When switching through is effected at the selector, a circuit is completed for relay 367 which extends as follows: battery, lower winding of relay 367, lead 729, normally closed springs controlled by armature 359, lead 482, negative trunk conductor, polarized relay in the junction

relay set, positive trunk conductor, lead 483, armature 363 and its back contact, normally closed springs controlled by armature 358, lead 728, upper winding of relay 367 to earth. Relay 367 is accordingly now operated but the polarized relay in the junction relay set does not operate at this time owing to the current flow being in the wrong direction. Upon the operation of relay 367, at armature 368 a circuit is prepared for relay 364 and at armature 369 a circuit is completed for relay 370 and this accordingly operates in turn and at armature 371 prepares a circuit for relay 309 over leads 702 and 703. After the junction has been assigned, a steady earth should be applied to the lamp lead and if this condition is duly fulfilled, relay 376 will be held over its top winding. In case, however, any irregularity should have occurred so that flash or flicker pulses are still being applied to the lamp lead, relay 367 will de-energize and will thereupon complete a circuit for relay 309 which locks up and gives the alarm as will be described subsequently. Relay 370 also at armature 372 prepares a circuit for relay 374, while at armature 373 relay 304 is connected over lead 734 to the test conductor 481 extending from the selector level for a purpose which will be described subsequently.

The sending of the numerical digits from the sender will now be initiated and accordingly relay 367 will pulse in response thereto, on each de-energization completing a circuit for relay 374 which owing to its slow characteristic holds up throughout the train. Thereupon at armature 375 earth is connected over lead 432 to the 13th contact in the bank of wiper 502 and when this is removed at the end of the train of impulses the test switch is advanced one step in the usual manner to the 14th set of contacts whereupon indicating lamp 547 is lighted. The further stepping of the test switch depends on the successful reception of the digits and also on the test which is made by means of relay 304 for guarding earth. The earth for maintaining the connection should be supplied at this time from the junction relay set and is therefore operative to shunt relay 304. If relay 304 remains deenergized, at armature 305 and its back contact earth is applied to the 14th, 15th and 16th contacts in the bank of wiper 502 over armature 375 and accordingly the test switch is advanced through these positions as the various digits are received. When the test switch is advanced to its 14th position after the reception of the first numerical digit, a circuit is completed from the earth on wiper 503 and over lead 460 for relay 357 and this upon operating, at armatures 358 and 359 connects relay 367 across the leads 482 and 483. That is to say the operation of relay 357, when the test switch is advanced to its 14th position, re-

verses the connections of relay 367 to the junction from the selector level, extending over leads 482 and 483, so that in case either the negative or positive conductor is in contact with the corresponding conductor of some other junction, this reversal will prevent relay 367 from responding to impulses and the test switch will accordingly be prevented from advancing. This operation only takes place for the reception of the second numerical digit and when this has been successfully completed, the test switch is stepped so that relay 357 is no longer energized. The third and fourth numerical digits are then received in a similar manner and the test switch is accordingly stepped to its 17th position. In this position indicating lamp 548 is lighted and the earth on lead 427 is also extended over wiper 503 and lead 465 to relay 360. The operation of relay 360 at armature 363 connects busy flash battery from lead 480 to the positive lead from the selector. Moreover at armature 361 contacts 331 of relay 330 are short-circuited so as to prevent undue delay in the operation of the alarm owing to the fact that this test is prolonged for three pulses of busy flash. The application of busy flash battery over the positive lead should result in the repeating back of a corresponding connection from the junction relay set that is to say the connection of battery to the lead coming into the routiner over wiper 627 of the junction distributor JD^1 . Hence since relay 352 is still locked up and therefore armature 355 is operated, a circuit is now completed for the lower winding of relay 385. Upon the operation of relay 385, at armature 388 a circuit is completed over wiper 502 of the test switch for relay 330 and when relay 385 releases, this circuit is broken and accordingly the test switch is stepped. In this manner it moves a further three steps and thus advances into its 20th position. A circuit is now completed for indicating lamp 549 and also from earth on wiper 503, by way of the 20th contact in its bank, lead 458, lead 723, front contact and armature 368, lead 723, and winding of relay 357 to battery. The operation of relay 357 as before reverses the connection of windings of relay 367. The operation of the polarized relay by connecting battery to the negative lead effects the operation of relay 385 and this as before operates armature 388 though in this case earth is extended over lead 739, lead 463 to the 20th contact in the bank of wiper 504 and thence over the interrupter contacts 508, lead 441, back contact and armature 313, lead 700, lead 439, winding of magnet 507 to battery. Accordingly magnet 507 operates and breaks its own circuit at contacts 508 and thus advances the wipers of the test switch into the 21st position whereupon indicating lamp 550 lights. The earth on wiper 503 is now extended over lead 459, winding of relay 364, lead 723, front contact and armature 368, lead 722, winding of relay 357 to battery whereupon relay 364 operates and relay 357 is maintained operated. At armature 366 relay 364 connects ringing current from the interrupted generator over the induction coil I to the positive lead 483 whence it is extended over the selectors used and through the condenser in the talking circuit to the corresponding contact in the bank of wiper 628 of the junction distributor JD^1 , lead 405, winding of alternating current relay 393 to earth. If the talking condenser is in proper condition, the ringing current thus transmitted is sufficient to cause the operation of relay 393 and this relay completes a circuit as follows: earth, front contact of armature 327, armature 394 and its front contact, lead 477, lead 752, 21st contact in the bank of wiper 502 and thence to operate relay 330 as before, so that the test switch is advanced to its 22nd position. Indicating lamp 551 now lights and relays 357 and 364 are de-energized and accordingly the current is reversed to its original direction over the junction line and the ringing lead and the alternating current relay 393 are disconnected. Upon the restoration of the current flow to normal, the polarized relay in the junction relay set releases and disconnects the battery feed thereupon releasing relay 385. The following circuit is now completed: earth, armature 392 and its front contact, armature 388 and its back contact, lead 741, lead 445, 22nd contact in the bank of wiper 504 and said wiper, interrupter springs 508, lead 441, lead 726 back contact and armature 313, lead 700, lead 439, winding of magnet 507 to battery. Accordingly the test switch is advanced to its 23rd position, in which position the earth on wiper 503 is extended over lead 457 to short-circuit relay 352 and this after a slight interval releases and at armature 354 disconnects the battery feed through relay 389. Since the line relay of the junction relay set is in series with relay 389, it will also restore at this time and open the junction lamp circuit so that relay 376 should also now restore. Moreover the earth on wiper 501 is now extended to the indicating lamp 541 to indicate the particular test in progress. When the test switch steps to its 24th position since the last two contacts in the bank of the homing wiper 506 are permanently connected to earth, it now returns to its normal position and relay 127 is again operated. The test switch is now operated in the manner previously described and earth through the interrupter 485 is connected over lead 453 to the first two contacts in the bank of wiper 502. Consequently testing for a free junction now recommences in the manner previously described and when such a junction is found the tests are carried out on it in

the same way. When all the junctions accessible over the junction distributor JD¹ have been either tested or found busy, the junction distributor JD² is brought into use and tests are made on the junctions accessible from its bank. When these have all been dealt with, another idle position is seized and the junctions associated therewith are rousted.

In order that an indication may be obtained at any time of the number of positions which have actually been rousted, the bank of switches such as SD¹, over which wiper 612 passes is multiplied to the bank of a routine indicating switch RIS as shown in Figs. 5 and 7. The routine indicating switch is stepped round, under the control of the routine indicating key RIK, the operating circuit for stepping magnet 516 being traced as follows: from battery, winding of stepping magnet 516, lead 95, contacts of routine indicating key, lead 96, armature 291 and its front contact, to earth, armature 291 being operated when the routine finish relay 285 is operated. Hence if the particular positions connected with in any position of the switch RIS have been rousted, the associated indicating lamps will be lighted, and thus an indication will be given of the progress of the test. Alternatively, instead of the switch RIS it would be possible to make use of six relays each carrying ten pairs of springs and adapted to make connections similar to those effected by the switch RIS. This arrangement would have the advantage that on the pressing of the key corresponding to the key RIK, all the lamps would be lighted at once.

The release alarm key RA is provided in order to enable the alarm to be disconnected after a fault has been found. It will be seen that earth is provided over the normally closed contacts of this key and leads 690 and 72 to lock up the alarm relay 309 which is operated as shortly to be described when a fault is found.

The re-start key RS enables the testing operation to be re-started after it has been stopped due to the distributors making a complete revolution without finding any positions idle and untested. At the left-hand springs of this key earth is then removed from lead 34 so as to open the locking circuit of the routine finished relay 285 while at the right-hand springs a point in the locking circuit of relay 152 is opened; consequently conditions are again restored for enabling the distributors to make a further test for positions which are idle and have not yet been dealt with.

It may be desirable in some cases to perform a continuous routine test upon a certain position or also upon a certain trunk particularly in case a fault has originally been encountered and it is now desired to see that it has been properly cleared. For

a continuous routine test of a particular position, the key PCR is operated before the start key SK and the former at its left-hand springs completes a circuit for relay 119 which operates and performs the functions previously described. At the right-hand springs of the key PCR, a circuit is completed from earth, armature 117 and its back contact, back contact and armature 156, right-hand springs of key PCR, winding of relay 137 to battery. Upon operating, relay 137 at armature 139 connects earth to the stepping keys, at armature 140 opens a point in the homing circuit of the secondary distributors, at armature 141 prepares a circuit for relay 285 and at armature 142 completes a locking circuit for itself. The group stepping key GS is now operated to move the primary distributor wipers into engagement with the required secondary distributor, the circuit extending from earth, front contact and armature 139, springs of key GS, lead 672, lead 68, lead 168, winding of magnet 607 to battery over lead 29 to the winding of relay 233. Then the position stepping key PS is operated and each time its contacts close a circuit is completed from earth at armature 139, contacts of key PS, lead 666, lead 27, wiper 605 to magnet 610 and thence to battery through relay 233 as before. When the required position has been connected with as indicated by the lighting of the corresponding lamp, the start key is thrown and upon the operation of the start relay 115, the circuit of relay 131 is completed at armature 116 and at armature 118 a circuit (which will not become effective in this case) is prepared for stepping the secondary distributor. Upon the operation of relay 131, the test proceeds in the manner previously described on the particular position selected. When all the junctions accessible over the first junction distributor have been rousted, relays 172 and 175 are operated as previously described and relay 175 serves to transfer the stepping circuit to the second junction distributor and locks up over its own armature 178. When all the junctions accessible from the bank of the second junction distributor have been tested, relay 166 is operated as before and opens the circuit of relay 175 at armature 169. While relay 175 holds up, however, a circuit is completed from earth, armature 179 and its front contact, lead 674, front contact and armature 170, armature 141 and its front contact, lead 64, back contact and armature 288, upper winding of relay 285 to battery. Relay 285 being of the two-step type operates its light armature 290 at this time, thereby short-circuiting its lower winding over lead 34 and the left-hand contacts of the re-start key. When relay 175 releases after its slow period the circuit of the junction distributor magnet is opened and it accordingly steps the associated wipers thereby opening the circuit

of relay 166 which also releases after a slight interval. Moreover at armature 170 the shunt earth is removed from the lower winding of relay 285 and it now operates fully thereby lighting the routine finished lamp and performing the other functions previously described. If it is desired to make a further test on the junctions in this position, the re-start key is operated whereupon 5 at the left-hand contacts of this key the locking circuit of relay 285 is opened and the previous conditions are restored.

In case it is desired to make a continuous routine test on a particular trunk, the key 15 TCR is operated instead of the key PCR. Thereupon at the left-hand contacts of this key a circuit is completed for relay 119 as before, while at the right-hand contacts earth from the back contact of armature 117 is 20 extended to the winding of relay 162. Relay 162 upon operating, at armature 163 opens the pulsing circuit for the junction distributor so that this shall not be advanced at the end of each test, at armature 164 applies 25 earth to the stepping keys and at armature 165 completes a locking circuit for itself. In addition to the keys GS and PS, it will be necessary in this case to operate also the key TS which completes a circuit which is readily 30 traceable for the magnet of the proper junction distributor. This test will continue on the trunk selected until the start key or the key TCR is restored.

In order to facilitate the location of faults, 35 the key FL is provided and when this is operated a circuit is completed for relay 119 as before and also relay 143 is operated. This at armature 144 supplies earth to the stepping keys in the usual manner and opens the circuit of the visible alarms, at armature 40 145 opens a point in the circuit of relay 131, at armature 146 prepares a circuit for relay 180, at armature 147 completes a locking circuit for itself, at armature 148 prepares a 45 stepping circuit for the auxiliary secondary distributor since as relay 131 will not be operated in this case no circuit is completed by it, at armatures 149 and 150 prepares connections over the auxiliary secondary distributor 50 to the order wires extending to the position in question and at armature 151 removes earth from the second group of multiplied contacts in the bank of wiper 606 of the test switch. Since relay 180 is not yet operated in this 55 case, this means that tests will start at position 13 of the test switch owing to the homing earth remaining connected to the first group of multiplied contacts. The attendant may now if he wishes by operating the appropriate stepping keys set the distributing switches on to any desired junction at any position and then operate the start key and observe from the supervisory lamps the progress of each test. When the test switch has 60 rotated to position 13, relay 180 is operated

over wiper 505 and the test then proceeds in the normal manner. It will be noted that when the attendant is locating faults, since relay 131 does not have to be operated, he may make connection with a position which is staffed, and may if he wishes insert the jack J in the plug P and order up a connection from the operator over a particular junction. It will be seen that when the jack is inserted in the plug, the transmitter and receiver of 70 a handset 89 specially provided on the routine are connected up to leads 76 and 77 and thence through the repeating coil windings to the upper and lower windings of the relay 395. This relay accordingly operates and at armature 396 connects up the other windings of the repeating coil in a circuit including armatures 149 and 150, 192 and 193 and leads 9 and 10 to wipers 639 and 640 of the auxiliary secondary distributor ASD¹. Moreover, at armature 397 a point is opened 75 in the auxiliary circuit for relay 180 and at armature 398 a circuit is completed for advancing the test switch to its thirteenth position. The attendant will then remove the jack J thus de-energizing relay 395, which at armature 397 permits relay 180 to operate and completes a circuit for the order wire supervisory lamp 90 thus indicating to the attendant that the test has commenced. 80

A description will now be given of a feature which may be advantageous in some cases. It will be seen from reference to British Patent 229765 that there are four sets of common apparatus which can be associated with the operator's position and since the switch termed the outlet finder advances one step for each call set up, if routine tests are to be made on all the common apparatus only four junctions at the position need be tested. Moreover, as previously pointed out, with the arrangement shown the capacity of the two junction distributors is 46 junctions and it is not desirable to provide more than two of these distributors. In case, however, there should be 50 junctions incoming to the position, the remaining four can conveniently be dealt with over contacts 1-4 of the first junction distributor, the changeover from junctions 1-4 to junctions 47-50 being made by 100 suitable relays. In the present instance the positions are assumed to be equipped with 50 junctions and accordingly the quick routine test is made over junctions 47/50. For this purpose the quick routine key QR is thrown, 105 whereupon at the right-hand contacts of this key a circuit is prepared for relay 159. Moreover, at the left-hand springs of the key QR, earth is extended over lead 687, lead 70, winding of relay 299, lead 71, armature 194 and its front contact, lead 4, wiper 645, lead 409, winding of relay 536 and winding of relay 535 to battery. The relays 535 and 536 it will be understood are associated with the particular position and may conveniently be mounted 110

130

adjacent to the battery feed relay 533: relay 299, however is located in the routiner and serves for all the positions. Upon the operation of relays 535 and 536 the leads from the first four contacts in the banks of wipers 625—628 are transferred to the lamp, assignment and positive and negative conductors of junctions 47—50. Moreover at armatures 300—303 of relay 299 the indicating lamp leads from the first four contacts in the banks of all the distributors JD¹ are transferred so as to connect up the indicating lamps connected with junctions 47—50 instead of those associated with junctions 1—4. 15 The test now proceeds in the usual way upon the operation of the start key and when junctions 47—50 have been rouined a circuit is completed over wiper 629 in 5th position, lead 83, lead 662, right-hand contacts of key QR, lower winding of relay 159 to battery. Relay 159 upon operating, at armature 161 locks up over its upper winding and at armature 160 brings down relay 131. The junction distributors are then moved to the "position rouined" contacts, that is, the 24th position of the second junction distributor, and the operation of relay 166 brings down relays 152 and 159 and allows testing to take place for the next free position on which the quick 20 routine test is made in similar manner. Hence it is possible by this means to make a quick routine test which will test all the common equipment at the operator's position and also junctions 47—50 and will only occupy a 25 fraction of the time required for the full test. It will be appreciated that in the case of positions equipped with 50 junctions, in order to test all the junctions it will first be necessary to make the full routine test which will deal with junctions 1—46 and subsequently to 30 make the quick routine test which will then deal with junctions 47—50.

The arrangements for giving an alarm may now be briefly dealt with. It will be appreciated that the advance of the test switch to initiate a test is dependent on the success of the previous test and that if the test switch remains in any position except its normal one for more than a predetermined interval, the 35 alarm will be given. A circuit may be completed for the lower winding of the alarm relay 309 over armature 377 in case the junction lamp does not receive full earth, as previously mentioned but in general relay 309 will be operated after a time interval under the control of relays 306 and 314. When relay 314 is operated, at armature 317 it connects an additional earth to the motor start lead 490 and at armature 315 connects up interrupter 316 to relay 306 and at armature 320 prepares a locking circuit for this relay. Relay 306 first operates its light armature 308 and subsequently also armature 307 thereby transferring the pulses to relay 309. If 40 the conditions persist, relay 309 operates in

due course locks up to the key RA at armature 312, at armature 313 opens the circuit of magnet 507 to prevent the test switch moving, at armature 311 lights an alarm lamp, and at armature 310 connects up an alarm bell, assuming relay 143 is not operated. It will be seen that the circuit prepared for the lower winding of relay 314 at armature 183 is opened by relay 330 each time that relay operates to step the test switch. The normally energized relays 278 and 280 associated respectively with the junction distributors and the primary and secondary distributors serve to supervise the operation of the magnets of these switches. In the case of the primary and secondary distributors, battery feed is through relay 233 and this at armature 234 connects earth to lead 58 and hence through lamp 283' to relay 314. Similarly battery feed relay 295 at armature 296 supplies earth through lamp 283. When the start key is restored, earth is connected over armature 123 to lead 57 and should relays 278 and 280 not operate in due course, relay 314 would again be operated and the alarm be given so that supervision is obtained of the return of the switches to normal. The routine finished lamp 284 also obtains its battery from relay 314 so that an alarm is given in case the attendant does not at once notice the lighting of the lamp. 50

It will be understood that armatures 196—204 of relay 195 and 206—213 of relay 205 are wired to the auxiliary secondary distributors ASD² and ASD³ in the same way as the corresponding armatures of relay 185 are wired to the auxiliary secondary distributor ASD¹. 100

What I claim as new and desire to secure by Letters Patent is:—

1. In a telephone system, automatic routine testing equipment for testing telephone apparatus, a hunting switch for associating said testing equipment with said telephone apparatus, means for testing idle ones of said apparatus in turn until all have been tested, and means responsive to the completion of a test on said one of said apparatus and the association of a special potential therewith for preventing the seizure of said apparatus again by said hunting switch. 105

2. In a telephone system, automatic routine testing equipment for testing telephone apparatus, a hunting switch for associating said testing equipment with said telephone apparatus over the bank contacts of said switch, means for advancing said hunting switch to test said bank contacts to find one associated with a piece of apparatus in condition to be tested, means for routine testing said piece of apparatus, and means for stopping said routine testing operation when no contact is found associated with a piece of apparatus not in condition to be tested. 120

3. In a telephone system, automatic routine testing equipment for testing telephone 130

- apparatus, means for associating said testing equipment with said apparatus, means for routine testing all of similar pieces of said apparatus in turn until all have been tested, means for seizing said apparatus through its normal means of use while it is being tested by said testing equipment, means for stopping a partially completed test when said apparatus is seized by its normal means of use, and means for completely testing said apparatus subsequent to its again becoming idle. 5
4. In a telephone system, automatic routine testing equipment for testing telephone apparatus, means for associating said testing equipment with said apparatus, said apparatus available at the same time to its normal means of use, means for testing all of similar pieces of said apparatus in turn dependent upon the busy or idle condition thereof, and indicating means associated with each piece of apparatus to indicate when the associated apparatus has been tested by said testing equipment. 15
5. In a telephone system, automatic routine testing equipment for testing telephone apparatus, means for associating said testing equipment with said apparatus when said apparatus is not in use over its normal means of access, means associated with said testing equipment for connecting a particular piece of apparatus with said testing equipment when said particular apparatus is in use over said normal means of access, and means for testing said particular apparatus with said testing equipment in cooperation with the user of said apparatus connected thereto over said normal means of access. 30
6. In a telephone system, automatic routine testing equipment for testing telephone apparatus, a hunting switch for associating said testing equipment with said telephone apparatus, means for testing idle ones of said apparatus in turn until all have been tested, means responsive to the completion of a test on one of said idle apparatus for preventing the seizure of said apparatus again by said hunting switch, a test relay associated with said hunting switch, and means for connecting a potential to one terminal of said test relay when said hunting switch encounters said idle apparatus. 45
7. In a telephone system, automatic routine testing equipment for testing telephone apparatus, a hunting switch for associating said testing equipment with said telephone apparatus, means for testing idle ones of said apparatus in turn until all have been tested, means responsive to the completion of a test on one of said idle apparatus for preventing the seizure of said apparatus again by said hunting switch, a test relay associated with said hunting switch having a pair of terminals, means for connecting a potential to one terminal of said test relay when said hunting switch seizes said idle apparatus, 55
- and means for connecting said potential to the other terminal of said test relay when said hunting switch reoperates and encounters said tested apparatus again. 60
8. In a telephone system, automatic routine testing equipment for testing telephone apparatus, means for routine testing all of similar pieces of said apparatus in turn until all have been tested, means for seizing said apparatus through its normal means of use while it is being tested by said testing equipment, means responsive to said seizure for stopping a partially completed test, and means responsive to the subsequent idle condition of said apparatus and the association of a special potential therewith for completely testing said apparatus. 70
9. In a telephone system, automatic routine testing equipment for testing telephone apparatus, means for routine testing in turn all of similar pieces of idle apparatus that are in condition to be tested, means for associating a special potential with said apparatus when it has been tested, means responsive to the associating of another special potential with said apparatus when it is busy for preventing the testing of said apparatus, and means for again associating all of said apparatus in turn with said testing equipment and responsive to said potential to prevent the retesting of said tested apparatus, and responsive to the absence of the potential associated with said busy apparatus and the subsequent idle condition thereof for routine testing said apparatus, said operation continuing until all busy pieces of apparatus have been routine tested. 80
